Lorke, Kellenbeck & Mecke
ATTORNEYS

UNITED STATES PATENT OFFICE.

FREDERICK BRACCO, OF LYNDHURST, NEW JERSEY.

PROPELLER.

Original application filed May 29, 1922, Serial No. 564,434, Patent No. 1,491,512, dated April 22, 1924.
 Divided and this application filed May 17, 1923. Serial No. 639,576.

To all whom it may concern:

Be it known that I, FREDERICK BRACCO, a citizen of the United States, and resident of Lyndhurst, county of Bergen and State of New Jersey, have invented certain new and useful Improvements in Propellers, of which the following is a specification.

My invention relates to propellers and has for its object to provide a novel and simple construction and arrangement in which the propeller is capable of being readily folded to an inoperative position when its services are not required. Other more specific objects of the invention will appear from the description hereinafter and the features of novelty will be pointed out in the appended claims. This application is a division of another application for a propeller filed by me in the United States Patent Office on May 29, 1922, Serial No. 564,434, patented April 22, 1924 No. 1,491,512.

In the accompanying drawings, which show several examples of the invention without defining its limits Fig. 1 is an elevation partly in section showing the invention with the parts occupying operative positions; Fig. 2 is a fragmentary section showing the propeller in a folded, in operative position; Fig. 3 is a section on the line 3—3 of Fig. 2 and Fig. 4 is a similar view on the line 4—4 of Fig. 1.

In the form illustrated in the drawings the blades 10 are carried by a plurality of sleeves rotatably mounted upon the propeller shaft and upon each other; that is to say the blades 10 are mounted respectively upon an inner sleeve 11 rotatable upon the hollow shaft 12, an intermediate sleeve 13 rotatable upon the sleeve 11 and an outer sleeve 14 mounted to rotate upon the sleeve 13 as shown in Figs. 1 and 2. The blades 10 are so arranged upon the respective sleeves as to occupy the relative positions required to constitute an operative propeller when said blades are unfolded, and so as to be capable of being rotated into surface engagement with each other in a folded, inoperative position. That is to say the inner sleeve 11 and its blade 10 are fixed upon the hollow shaft 12 for instance by means of a key 15 while the sleeves 13 and 14 are each capable of being rotated about their common axis to fold their blades 10 into engagement with the first-mentioned blade 10 and with each other and to unfold said blades

to an operative position; any suitable means may be utilized for actuating the sleeves to adjust the blades 10 to the operative and inoperative positions. To arrest the movements of the sleeves 13 and 14 and their blades 10 at the proper points, said sleeves may be provided with pins 16 which extend into recesses 17, the opposite closed ends of which provide stops against which said pins abut.

The blades 10 may be locked in their operative and inoperative positions in any convenient way; in the illustrated example the locking means comprises an auxiliary shaft 18 located within the hollow shaft 12 and provided at its outer end with a head 19 which in turn carries one or more locking members 20. The latter co-operate with one or more apertures 21 with which the sleeves 11, 13 and 14 are provided, said apertures being so located as to register with each other in the operative and inoperative positions of the blades 10 as shown in Figs. 1 and 2; that is to say the locking members 20, by projecting through the registering apertures 21, as illustrated in Figs. 1 and 2, prevent rotation of said sleeves relatively to the shaft 12 and to each other and thus lock said blades 10 in either and both of their positions. A pin 12^a projects inwardly from the shaft 12 into a groove 18^a extending lengthwise of the shaft 18 and thus fixes the latter against rotation relatively to the shaft 12 without interfering with the required lengthwise movements of said shaft 18. With this arrangement the locking members 20 occupy a constant, fixed relation to the apertures 21 and are in proper position to enter said apertures in either position of the blades 10. The mechanism whereby the auxiliary shaft 18 is adjusted relatively to the hollow shaft 12 to shift the locking members 20 into and out of said apertures 21 may be of any convenient type; for instance, as shown in the illustrated example, an internally threaded hand wheel 22 may be rotatably mounted upon the hollow shaft 12 in a manner to be incapable of axial movement relatively thereto, in which case the inner end of the auxiliary shaft 18 is screwthreaded, as indicated at 23, for co-operation with said hand wheel 22. In the present instance the hollow shaft 12 is fixed against lengthwise movement by means of collars 24 and a flange 25 fixed upon the stern 26 of the vessel; a gear 27 is mounted

upon the hollow shaft 12 for operatively connecting the same with a source of power.

In practice the hand wheel 22 is rotated in a direction to shift the shaft lengthwise 5 of the shaft 12 to withdraw the locking members 20 from the apertures 21 and permit the folding and unfolding of the blades 10 under which said wheel 22 is operated in the reverse direction to again shift said 10 locking members 20 into said apertures 21 and thereby lock said blades 10 in whatever position they may occupy at the time.

It will be obvious that if desired the number and arrangement of blades upon a given 15 sleeve, may be otherwise than as shown without in any way departing from the spirit of the invention. In their folded inoperative positions, in which the blades 10 lie in approximately surface engagement 20 with each other, the group of blades rotatably drop, by gravity, to a position in line with the rudder of the ship and thus offer a minimum of resistance to the progress 25 of the vessel when the latter is, for instance, under sail.

The invention is simple in construction and efficient in operation and provides an arrangement whereby the propeller blades may be easily adjusted from an operative 30 to an inoperative position and vice versa in a minimum of time and with comparatively little effort. The invention is particularly adapted for use in vessels provided with both sail and power and permits 35 the propeller to be quickly folded when the ship is operating under sail thus eliminating drag and other objectionable features tending to interfere with the progress of the vessel. The illustrated and described propeller arrangement may be also utilized 40 in connection with aeroplanes and airships and anywhere else where a folding propeller is desirable.

The principal purpose of the invention is 45 to provide a propeller construction in which the propellers are capable of convenient and practical adjustment in a manner to make them dependable for intermittent periods of service and so as to have their bulk so reduced or removed when not in use, as to 50 reduce or eliminate the drag without requiring a complete dismantling of the propeller and its associated parts. It will be understood that the illustrated example is 55 intended to exemplify the invention without arbitrarily restricting the elements thereof or the construction and operation of the same.

It may be stated that the invention is 60 especially useful in that it provides a novel and efficient means whereby close maneuvering is possible, at will, either with sail or power alone or with both sail and power.

This introduces into ship's drills a new element and with it a new set of tactics which 65 will assist materially in veering and navigating in close quarters and prove of great usefulness in also imparting to ships or vessels, for intermittent stretches under proper conditions, the advantage of propulsion by a combination of sail and power. All of the above will further result in increased speed of travel, with an increased average speed thus reducing the time of travel from port to port, providing a greater 75 control of the factors of navigation and a maximum operative economy.

Various changes in the specific form shown and described may be made within the scope of the claims, without departing 80 from the spirit of my invention.

I claim:

1. The combination of a shaft, a plurality of propeller blades mounted thereon and located in a common circumferential plane, 85 said blades being rotatably adjustable relatively to each other to a folded inoperative position in which all of said blades extend in the same direction and lie contiguous to each other and to an unfolded operative position and means for locking said blades in either position.

2. The combination of a hollow shaft, a plurality of collars rotatably mounted upon 95 said shaft and upon each other, propeller blades carried by said collars and located in a common circumferential plane, said blades being adjustable by said collars, in said common plane, to an unfolded, operative position and to a folded inoperative 100 position and means located partly within said hollow shaft for locking said blades in either position.

3. The combination of a hollow shaft, a plurality of collars rotatably mounted upon 105 said shaft and upon each other, propeller blades carried by said collars and located in a common circumferential plane, said blades being adjustable by said collars, in 110 said common plane, to an unfolded, operative position and to a folded inoperative position, said collars being provided with apertures adapted to register with each other in each position of the blades, an auxiliary shaft slidably mounted within said 115 hollow shaft, a head carried by said auxiliary shaft, locking members projecting from said head and adapted to enter said apertures to lock said blades in either position and means whereby said auxiliary shaft is 120 slidably actuated to shift said locking members into and out of said apertures.

In testimony whereof I have signed this specification.

FREDERICK BRACCO.
